Patented in the United States of America, Patent Office
by Harry U. Bates and John T. Perkins, Los Angeles, Calif., on November 14, 1950, Serial No. 785,454, filed November 12, 1947, and assigned to the United States of America, represented by the Secretary of the Army, Washington, D. C.

UNITED STATES PATENT OFFICE

TOILET SEAL FOR AUGMENTING THE FLUSHING CAPACITY OF TOILET TANKS IN UNSTOPPING SEWERS

Harry U. Bates and John T. Perkins, Los Angeles, Calif.; said Bates assignor to Jess E. Teel, Los Angeles, Calif.

Application November 12, 1947, Serial No. 785,454

1. Claim. (Cl. 4—257)

Our invention relates to a toilet seal for augmenting the flushing capacity of toilet tanks in un-stopping temporary stopped-up sewers.

The invention also pertains to new steps in the method of unstopping a clogged sewer.

It is not infrequent that patrons, especially of service stations, public toilets, and often-times the same habit is practiced in hotels and apartment houses of throwing into the toilet bowl discarded sanitary napkins, which together with toilet seat covers and the use of newspaper toilet paper and the like after repeated performances temporarily stop up the toilet bowl and sewer thereby necessitating calling in the service of a plumber or plumber's assistant to remove the stoppage.

The practice of having to call in the plumber from time to time is an expensive one and if the defect is not remedied at once it soon creates an unsanitary condition which is injurious to the public welfare.

Accordingly, it is a paramount object of this invention to provide means for closing air-tightly the mouths of conventional water closet bowls to augment the flushing capacity of a toilet tank by compressing the entrapped air in the bowl as a result of the water flowing into the bowl, until the combined built-up pressures of water and air become great enough to flush away any minor stoppage in the closet bowl and/or in the sewer line adjacent thereto to remove obstacles of the like aforementioned.

Further objects include a device having a new mode of operation and a new mode of assembling and whose function is entirely different from anything heretofore contemplated.

Also, it is an object to provide new steps in the method of blowing out obstructions temporarily stopping up toilet bowls and sewer lines.

Other objects, advantages and features of invention will hereinafter appear.

Referring to the drawing wherein is shown a preferred embodiment of the invention,

Fig. 1 is a perspective view of a water closet and toilet bowl equipped with the improved device, a portion of the floor upon which the toilet bowl rests being broken away to expose the closed-off sewer.

Fig. 2 is an enlarged fragmentary section on line 2—2 of Fig. 1.

Fig. 3 is an exploded perspective view of the parts for connecting the toilet seal to the toilet bowl apart from the toilet seal.

Fig. 4 is a perspective view of the toilet seal per se on a scale similar to that shown in Fig. 1.

Referring in detail to the drawing and first to Fig. 1, included among the conventional parts are the water closet bowl B, the water closet C connected to the closet bowl, the water intake line W, the handle H for flushing the bowl, and the sewer line S into which the flushing water and waste matter from the bowl flows.

As shown in Fig. 2 the rim of the bowl B is equipped with a downturned flange F extending inwardly around the bowl.

The toilet seal 4 includes a cover plate 5, a gasket of thick spongy rubber underlying said cover plate in a fixed relation thereto, an elongated threaded bolt 7, the end thereof opposite its head extending upwardly through the cover and gasket, an elongated locking bar 8 swingably carried by the bolt head 9 in a downwardly spaced relation to said plate and gasket, a lock nut 10 to secure said bar fixedly to said bolt head, a wing nut 11 pinned to the threaded end of the bolt whereby to rotate said locking bar relatively to said down-turned flange for locking and unlocking the latter bar therewith, the wings 12 of said wing nut extending in the same direction as the locking bar, and a jamb nut 13 interposed between said cover plate and wing nut for screwing downwardly upon said cover plate to compress the gasket into an air tight relation with the rim of the bowl after the bar has been manually rotated through the medium of the wing nut into a locking relation with the flange F as shown in Fig. 1.

The toilet seal is of a shape and size so as to completely cover the rim B of the bowl, the locking bar being of such length so as to underlie the flange F when rotated into the dotted position shown in Fig. 1, which is in a line with the short axis of the toilet seal. When the bar is rotated to a position at right angles to that shown in Fig. 1 which is the long axis of the toilet seal, the ends of the bar are free of the flange and the apparatus can be removed from the toilet bowl.

In the position of the parts shown in Fig. 1, the jamb nut can be rotated clockwise to clamp the locking bar against the flange F and thereby compress the gasket, and when the jamb nut is loosened, by reversing its rotation, the locking bar can be rotated so as to coincide with the long axis of the toilet seal wherein the device can be detached as aforesaid, the wings of the wing nut in each instance being utilized to denote the direction in which the locking bar extends in relation to the toilet seal.

When the device is in the operative position

shown in Fig. 1, by depressing the handle H and flushing the toilet tank the water flowing into the bowl will compress the air entrapped therein to augment the flushing action of the tank.

With regard to the new steps in the method of un-stopping a clogged sewer, the mouth of the toilet bowl is first air-tightly closed entrapping the air therein, and then the toilet tank is flushed to compress the air to augment the flushing action of the water.

It will thus be seen from the foregoing that an extremely simple device has been created for providing new and useful results not heretofore contemplated, that the peculiar mode in which the elements are assembled provide new and useful results for indicating the direction in which the locking bar extends at all times, and that through the new use to which the device is put new and unobvious results are achieved in the manner in which the device coacts with the flushing operation of the tank to move obstacles temporarily clogging a drain.

We claim:

In a removable closure for sealing the top opening of a water flushed closet bowl to provide an air tight chamber for pressure flushing of the discharge from the bowl, said bowl having means at the edge of its top opening adapted for engagement with a clamping member, a rigid plate shaped to fit on the top of the bowl and to completely cover the top opening thereof, resilient sealing means on the underside of said

plate, said plate and sealing means having aligned openings therethrough, a threaded stem extended through said openings so that said sealing means resiliently presses against the stem and seals the opening in the plate about the stem, a clamping bar fixed to the lower end of said stem operative to engage and disengage the clamp engaging means of the bowl, a nut threaded on the stem so as to bear against the plate for releasably holding the bar in closure clamping position for clamping the plate on and releasing the plate from the bowl, the clamping position compressing part of the resilient means between the margin of the plate and the top edge of the bowl, and a winged member fixed on the upper part of the stem operative for turning the stem and clamping bar to clamping and releasing positions, to hold the stem during tightening of the nut, and to indicate the position of the clamping bar under the plate.
